UNITED STATES PATENT OFFICE

2,142,261

MOUNTING FOR CARDS, PHOTOGRAPHS,
AND THE LIKE

Albert A. Ainsworth, Ossining, N. Y.

Application July 10, 1935, Serial No. 30,616

5 Claims. (CL. 129—19)

The invention relates to the art of mounting and filing papers, photographs, autographed cards, clippings, samples, scrapbook entries and other slips or articles of paper, cloth, or other 5 fabric or material, and is intended primarily as an improvement on the inventions set forth in my prior Patents Nos. 1,461,570, July 10, 1923 and 1,862,450, June 7, 1932. The present application is a continuation in part of my application Serial 10 No. 699,730, filed November 25, 1933, relating to Hinged cards, now Patent No. 2,038,468 dated April 21, 1936, which patent may be referred to for further details of construction. In such 15 patent there is disclosed the novel combination of a stiff backing and rows of relatively flexible card holding tongues projecting from the backing adapted to serve as hinges, and relatively stiff cards adhesively secured to the tongues which 20 cards are adapted to be turned back and forth about the tongues as hinges. The patent also discloses the feature of attaching the cards to the undersides of the tongues, then turning the cards over about the tongues as hinges, the cards 25 when assembled being arranged in battery. This arrangement is particularly useful in the case of photographic albums as the individual cards stand out and each is readily accessible and may be turned back about the tongues as hinges. These features form part of the present invention. 30

In common with my Patent 1,862,450, I prefer to employ a backing or folder of comparatively stiff material having one or more strips of tough, 35 flexible material secured to the backing and having tongues or tabs for adhesively retaining the slips or articles to be filed, although so far as the broad aspects of the invention are concerned, the backing itself may be provided with the improved forms of tongues, as in my earlier Patent 40 1,461,570, and the slips or cards may be secured directly to such tongues without departing from the spirit of my invention.

The broad object of the invention is accordingly to improve the mountings disclosed in my 45 aforesaid patents and to furnish a quick, easy, economical and permanent method of mounting cards, newspaper clippings, photographs, snapshots, office data and the like in a convenient overlapping manner so that a portion of each 50 article when mounted is always visible, and also so that when turned back the contents written or printed on one or both sides of the mounted article are clearly visible.

A more specific object of the invention is to 55 improve the form of tongues or tabs employed in

the mounting so as to give additional mounting strength. A further object is to provide means for securing perfect alignment of the cards, photos, etc., without the necessary use of guide lines. Another specific object of the invention is to provide, in combination with a backing, a plurality of separate and individual mounting strips, each adapted to carry a single card or the like, such strips with the cards mounted thereon being arranged in battery upon the backing in such a 5 manner that the cards overlap one another with portions of each card visible. A further object is to provide a mounting strip with tongues which are easily folded back. Still another object is to provide a cheap and economical method for forming a plurality of the individual strips from a sheet of material without the loss of any of such material. 10

Other objects of the invention will be apparent from the accompanying drawings and the following detailed description, in which are set forth for the purpose of illustration various specific embodiments of the inventive thought involved, it being understood that these specific embodiments are intended as illustrative only and not as limiting the invention. 15

In the drawings,

Fig. 1 is a face or inside view of a backing or folder having cards or slips hingedly secured thereto by means of gummed strips; 20

Fig. 2 is a lengthwise section on line 2—2 of Fig. 1;

Fig. 3 is a fragmentary section on an enlarged scale showing a portion of Fig. 2 and indicating in detail the manner of attaching the cards or slips; 25

Fig. 4 is a detailed fragmentary view similar to Fig. 1, but showing only a single gummed strip applied to the backing;

Fig. 5 is a rear view of one of the individual gummed strips or mountings shown separate from the backing; 30

Fig. 6 is a front view of the same;

Fig. 7 is a similar view of a modified form of mounting strip;

Fig. 8 is a front view of another modification; 45

Fig. 9 is a view generally similar to Fig. 1, but showing a still further modification of the invention;

Fig. 10 is a front view of a portion of a sheet of mounts or hinges of a different form; 50

Fig. 11 is a rear view thereof;

Fig. 12 is a section taken on the line 12—12 of Fig. 10;

Fig. 13 is a section taken on the line 13—13 of Fig. 10; 55

Fig. 14 illustrates a card or backing on which different unit mounts are applied in various ways.

Fig. 15 is a section on line 15—15 of Fig. 14, showing both ends of the mounting strip pasted to the card;

Fig. 16 is a similar view on line 16—16 of Fig. 14, showing only one end pasted down, and

Fig. 17 is a similar view on line 17—17 of Fig. 14, showing a battery of hinges pasted by one end only.

Referring in detail to the drawings, the reference numeral 10 denotes generally a backing preferably composed of comparatively stiff material and which may constitute one or both covers of an album or other filing folder or the leaves thereof. As shown, the backing is provided with vertical and horizontal guide lines to assist in the alignment of flexible mounting strips 11, although owing to the peculiar construction of the preferred forms of mounting strips, once the first strip has been properly placed the other strips are practically self-aligning. These strips may be formed of tough flexible material, as paper, cloth or other fabric, and as shown are provided with a plurality of hinged tabs or tongues or the like 12, which serve for the attachment of cards, slips or the like 13. As shown in Fig. 5, the strip 11 is gummed on the back, the gummed portion including also the surface of the tongue 12. As shown in Figs. 1 to 7, the strips are elongated in form and the tongues are separated from each other by a space whose area is substantially equal to the area occupied by the tongue itself. Each strip is intended for mounting a single card or slip, one strip being applied at a time and the card 13 applied thereto. The strips with their cards or slips are secured in vertical alignment so that the individual strips form substantially a single strip secured to the backing, while the cards carried thereby overlap one another, as best illustrated in Figs. 1 and 2.

To facilitate bending or hinging the tongues 12 a cut or incision 14 is made through the body of the strip, which cut, in the form illustrated in Figs. 1 to 6, is straight sided and substantially U-shaped, the cut forming an inner tab or sub-tongue 15, which serves to give additional binding or adhesive power. Thus the flexible hinge is protected against the leverage of the comparatively stiff mounted card, which tends to pry the gummed strip from the base to which it is secured as the card is reversed by turning the same back about its hinges.

It will be noted that the tabs 12 hinge on lines 16—16. This permits the tabs 12 upon which the card is to be mounted to be turned back easily so as to receive the card, and when so turned back the tongues 12 extend at an angle to the sub-tongues 15 and the pairs of tabs or tongues form a straight mounting edge against which the article to be mounted is placed while the tongues are secured thereto, and by this feature all mounted articles are automatically kept in alignment.

The tongues may be cut in other forms without detracting from all the advantages of the preferred form above described. For example, in Fig. 7 a single straight slit 14a takes the place of the three-sided slit 14, and while no sub-tongue is formed in this embodiment of the invention, the mounting tongues 12b may be bent back easily as in the previously described embodiment and alignment of the cards and strips is likewise secured.

Both the main and sub-tongues of the mounting strips may be formed in various shapes. They may, for example, be V-shaped or rounded. The forms having tongues with straight sides, however, possess the advantage of economy over the forms with rounded tongues, as nearly twice as many tabbed mounting strips may be cut from the same material as would be possible with rounded tabs. In the forms shown in Figs. 1 to 7 it has been noted that the space 17 between the tongues is of substantially the same area as that of the tongues themselves including the sub-tongues where present, and likewise the end spaces 18 extending beyond the tongues are substantially half the size of the tongues. Thus the material forming the tongue of one strip leaves a space between tongues for the next strip, where a plurality of said strips are cut from a continuous sheet or strip of material. In this construction likewise the side extensions 19 will be noted. These projecting portions serve to give additional strength to the entire mount.

The number of tabs or tongues employed may be varied as desired, but preferably two or more are used to secure proper alignment.

In Fig. 8 a strip 11a having three tabs or tongues 12a is shown, these tongues being of simple V-shape and lacking many of the advantages of the preferred form in that there are no minor or sub-tongues formed and no means are provided to facilitate bending of the tongues and for securing alignment of a group of the tongues in battery. It will be understood that one side of the strip 11a including the tongue portions is preferably provided with adhesive material, as in the embodiment shown in Fig. 5.

The method of utilizing the mounting strips will be apparent from the foregoing description. The first mounting strip of the series may be secured to the backing as illustrated in Fig. 4 of the drawings, with the body of the strip and the sub-tongues securely fastened to the backing, leaving the main tongues 12 accessible for the mounting of the card. The card is then applied as illustrated in Figs. 1, 2 and 3, whereupon another mounting strip may be secured in place just below the first strip. It will be noted that the sub-tongues 15 of one strip will be covered by the body portion of the next mounting strip. In this manner a substantially continuous strip will be formed by the successive individual strips, and each individual strip will be firmly held down by the next individual strip, which overlaps the sub-tongue portions. Also the tongues of each strip serve as a straight edge for the mounting of the card and also assist in the alignment of the next individual strip. Where cards, slips or the like of uniform size are employed, exposed spaces 20 of each will be visible, as best illustrated in Fig. 1, and on these visible portions suitable identification data may be placed if desired. The cards may be turned in either direction so as to expose matter printed or written on either or both sides thereof. This is particularly useful in the case of photograph albums, permitting photographs to be mounted on each side of the card. The stiffness of the card as compared with the hinge causes the flexure to take place entirely within the hinge.

If desired, the individual strips may be mounted with the main tongues pointing upwardly instead of downwardly, in which case the cards are mounted from above and are then reversed together with the hinged tongues or tabs. For

other types of mounting strips the reversed mounting may be employed.

In Fig. 9 a further modification of the invention is disclosed wherein a mounting strip 21 is employed having three rows of tongues, the two outer rows of tongues being represented by the numerals 22, 22, and pointing upwardly, while the tongues 23 of the intermediate row point downwardly. As shown, the outer tongues 10 are alike and are substantially V-shaped, and the point of one tongue extends into a space cut from the next adjacent tongue. The tongues 23 are likewise V-shaped, but do not extend into the adjacent tongues of the same row. The hinge 15 line of the two outer tongues and the intermediate tongue is continuous and, as illustrated, a card 24 is adapted to be retained by the conjoint action of the two outer tongues, which are preferably secured to one face of the card and the 20 intermediate tongue secured to the opposite face. It will be noted that, as in the previously described preferred embodiment of the invention, the form herein shown secures alignment for the individual cards which are firmly secured in 25 place without danger of coming loose. After being mounted the cards with the hinges to which they are secured are turned downwardly so that when a plurality of cards are employed in battery the lower edges overlap, as in Figs. 1 and 2.

30 While it is contemplated that the strip 21 may be of flexible material gummed on the back and may be adhesively secured to a suitable backing, a plurality of individual strips of similar construction, each having three or more tongues with 35 their bases in alignment, two of the tongues pointed in one direction and the other in the opposite direction, may be employed and arranged in battery, or tongues similar in shape to the tongues 22 and 23 may be cut into a backing or folder itself, as in my prior Patent 1,461,570.

The invention has been described in detail for the purpose of illustration, but it will be obvious that many variations may be resorted to 45 without departing from the spirit of the invention. For example, in mounting the strips the backing might be gummed and the strips ungummed. Also the various forms of tabs or tongues may be formed in the backing and provided with accessible gummed portions. The 50 cards or slips may be provided with gummed portions to fit the tongues on the mounting strips, in which case the tongues on the mounting strips need not be gummed. These variations are applicable to the various forms and 55 modifications herein disclosed. The cards, slips or the like 13 may be, if desired, formed with slots, slits or other means for receiving minor cards to be detachably engaged therewith, and 60 where the cards 13 are of substantial thickness means may be provided for preventing buckling, as described in my application Serial No. 699,780.

A further modification of the invention is shown in Figs. 10 to 17 inclusive, wherein mounts 65 are illustrated which are preferably provided with non-drying adhesive, so that cards, slips, stamps or the like applied thereto may be removed when desired. Such a mount is especially useful to stamp collectors. A convenient method of forming individual mounts from a large sheet containing a plurality of such mounts is also illustrated. Figs. 10 to 13 illustrate the method of 70 forming the mounts and Figs. 14 to 17 inclusive illustrate the application or use of such mounts 75 in connection with a card or backing.

Referring particularly to Figs. 10 to 13, the reference numeral 30 denotes a sheet of fabric or tough flexible paper. This sheet is provided with openings 31 arranged in horizontal and vertical rows. Intersecting lines 32 are formed horizontally and vertically, dividing the sheet into unit mounts. The lines may be woven into the fabric of contrasting color, if desired, or the sheet may be perforated to permit the units to be torn apart, or the lines may be ruled on the surface of the sheet. The sheet is gummed on one side with suitable adhesive 33, preferably of a character to secure a substantially permanent connection with a member to which it is applied. Across the adhesive face of the sheet 10 are arranged at intervals a plurality of strips 34 of what is known as Scotch tape, such strips being provided on one face with an adhesive 35 which may be of non-drying character and is 15 designed to permit removal of slips or other articles applied to the adhesive, as contrasted with the adhesive 33, which provides a relatively permanent connection. It will be noted that the adhesive 35 shows through the openings 34. The strips of Scotch tape are preferably not gummed 20 on the back.

The sheet 36, which comprises a plurality of unit mounts, is designed to be furnished to customers for application to a suitable backing. The sheet may be cut into a plurality of individual 30 mounts 36, each including one or more rectangular openings with the adhesive 35 showing through the said openings. It will be understood that these mounts may be cut in rows or as individual units, or may be cut in square or oblong 35 form with a plurality of the openings for attachment of slips or cards carried thereby.

In Figs. 14 to 17 various means of attaching the mounts to a backing 37 are illustrated. This backing is preferably of comparatively stiff material, and may, if desired, constitute one of the leaves or covers of an album.

At the upper left and center of the card or backing unit mounts 36 are shown applied with both of the ends of the mounts pasted to the 45 card. In the figure at the upper left a slip 38, which may be a postage stamp or the like, is illustrated in dotted lines, such slip being releasably attached to the adhesive face 35.

At the lower portion of the card a plurality 50 of unit mounts 36 are shown in horizontal alignment. These mounts are pasted to the backing along one end only so that the mounts can be swung upwardly along the line of pasting. In such a mount both the front and rear faces 55 are accessible for the attachment of slips or cards. To the front face a slip may be removably attached, while to the rear face a slip may be permanently attached along the lower edge thereof.

At the right of the card a number of unit 60 mounts are shown arranged in battery relation, each unit being pasted along one end only. In such arrangement both the front and rear faces are accessible for attachment of cards or slips.

It will be understood that any number of 65 mounts may be formed on a single sheet 30, such sheets being conveniently made up in units of 100. Where the sheet is of fabric, such fabric is woven of the right texture so that the meshes 70 will be ready for the Scotch tape to be mounted, as shown in the drawings. Also the strips 34, instead of being of the Scotch tape type provided with a non-drying adhesive, may be provided 75 with a permanent adhesive so that stamps, cards,

slips or the like may be permanently secured to either face when the units are hingedly mounted or to the front face when the mounts are secured along two sides.

5. It will also be understood that the unit mounts of the other forms described in connection with Figs. 1 to 9 inclusive may be provided with non-drying adhesive at the portion to which a card or slip is to be attached, or may be provided on 10 one face with a permanent type adhesive and on the other face with a non-drying adhesive. For example, in the form shown in Fig. 5, the tabs 12 may be provided with non-drying adhesive, permitting removal of the article applied thereto, 15 while the portions of the strip which engage the backing are coated with an adhesive which will rigidly adhere to the backing. It will be understood that these mounts may be coated on the back with an adhesive which will insure a firm 20 attachment to the backing, while on the front face a non-drying adhesive may be employed to permit removal of the card, slip or the like.

Further variations and modifications of the invention will be apparent to those skilled in the art.

25. What I claim is:

1. A mounting strip for filing cards, slips or the like composed of tough flexible material and comprising an elongated body portion adapted 30 to be secured to a suitable backing, spaced slip holding tongues projecting from the body portion, and sub-tongues within the first mentioned tongues adapted to be secured to the backing and serving to increase the adhesive strength of 35 the mount.

2. A mounting strip as set forth in claim 1 wherein the longitudinal edges of the strip are straight and parallel, and the slip holding tongues are arranged to swing about one edge of the strip as an axis, whereby the tongues constitute 5 a straight edge to insure proper mounting of the slips.

3. A mounting strip as set forth in claim 1 wherein the margins of the sub-tongues are parallel with the margins of the slip holding tongues. 10

4. A plurality of strips as defined in claim 1, arranged in battery upon a backing, with the sub-tongues of one strip covered by the body portion of the next strip and with the slip holding tongues unobstructed. 15

5. A mounting or filing device for cards, slips or the like, comprising, in combination with a continuous, unslotted, stiff backing, a plurality of flexible individual mounting strips adhesively secured in battery to the backing, and a plurality of individual cards carried by said strips, one mounting strip being employed for mounting each card, and the cards, when mounted, being in overlapped relation, with a portion of each card visible and extending beyond the next preceding card of the series, each mounting strip being provided with a plurality of spaced projecting tongues having exposed gum portions to which the card is secured, wherein each of the first mentioned tongues is hinged, and a plurality of sub-tongues within the first mentioned tongues secured to the backing and serving to increase the adhesive strength of the entire mount. 25

ALBERT A. AINSWORTH. 35
